UNITED STATES PATENT OFFICE.

LULU CASE, OF BERKELEY, CALIFORNIA.

NOVELTY DOLL.

Application filed February 19, 1923. Serial No. 620,045.

To all whom it may concern:

Be it known that I, LULU CASE, a citizen of the United States, and a resident of Berkeley, county of Alameda, State of California, have invented a new and useful Novelty Doll, of which the following is a specification.

My invention relates to a novelty doll and has for its primary object to utilize certain existing materials which while ordinarily produced for other purposes happen to offer an opportunity of utilizing the same in producing a doll without in any way destroying the intended use of the materials should the purchaser desire to take the doll apart.

To more clearly explain the salient features of the invention and the use that I have made of the materials required I propose to take an ordinary so called wash cloth and a cake of soap and without in any way destroying or otherwise impairing their intended use produce a unique novelty doll with the assembly of the materials so accomplished that the user may take the doll apart so as to speak and use both the wash cloth and the cake of soap in the customary manner.

In the accompanying drawing which illustrates the preferred embodiment of the invention Figure 1 is a perspective view of the assembly, Figure 2 is a detail view showing the finished folding or arranging the cloth to produce the garment or body portion of the doll and Figure 3 is a detail perspective view of a cake of soap used for the doll's head.

Figures 4, 5, 6, and 7 show progressive steps in folding the cloth.

Referring now to the drawing in detail (A) represents an ordinary wash cloth, best shown in its original form in dotted lines in Figure 2, (B) represents a cake of soap as best shown in Figure 3 and (C) represents the box or container in which the assembly is offered for sale and which also co-operate to better hold the doll in assembled condition.

In assembling the arrangement to produce the body of the doll from the wash cloth I prefer to fold the cloth (A) to leave the edges (A¹) meeting along a medial line so as to produce the front decorative seam (A²) of the garment. The bottom of the double thickness thus produced by the fold described may be turned up as best shown

at (A³). To produce the hooded cape effect (A⁴) the double thickness at the top of the cloth may be folded upon itself to leave shoulders (A⁵) and a pocket (A⁶) for the reception of the cake of soap (B) with the pocket simulating a hood for the doll's head.

In producing the body from the cloth emphasis should be laid on the fact that the cloth is not cut or manipulated in any manner whatsoever that will destroy its usefulness as a wash cloth if the doll is ever taken apart. The cake of soap (B) should in most cases ordinarily be round and one side of the same is painted to simulate a doll's face as shown.

Since the cake of soap is solid and consequently quite heavy as compared to the cloth I suggest that the hood be so formed as to tightly fit around the soap so that the face will not be displaced, and as the assembly is offered to the trade in a container the soap may be very nicely anchored, so to speak, in the container by sewing or otherwise fixing the body to the container as best shown by the stitches (A⁷) in Figure 2. To maintain the hood and cape effect as well as to hold the soap in place stitches (A⁸) may be taken in the folds of the cape but these stitches need not necessarily extend through the container. The fixing of the body to the container as well as the stitches (A⁸) hold the soap in place and also properly support the body in the container.

The face on the soap may be produced by hand painting, stamping or in any other way that will prove to advantage.

The steps in folding the wash cloth to form the combined doll body and garment are shown in Figures 4, 5, 6 and 7.

In considering these figures it should be observed that a wash cloth is of soft thick rough material of the general form shown in Figure 4 and it is to a certain extent the nature of the material which makes possible the final clothed body form as shown complete in perspective in Figure 1 and where the evident bulk of the body is due to the doubled thickness of the folded thick cloth, and the cowl or hooded cape is obtained by forming the upwardly turned top edges into an open pocket and tensioning the pocket by seams A⁸ and at the bow A⁹.

The cloth shown in Figure 4 is first folded side edges A¹, to meet along the line x-x as shown in Figure 5. Then the lower

edge A^{10} is folded upward to the line $xx-xx$ to form the article shown in Figure 6.

A few light stitches are taken along the 5 folded meeting edges A^1 either before or after turning up the lower end.

It will now be observed that the upper end forms a tubular body open at (11) and for a distance down the meeting line of the 10 edges A^1 .

This upper open end is brought at right angles to the plane of the body by turning the free corners (12) downward, as progressively indicated by the dotted lines a, b, c, d 15 on Figure 6, and tucking it under at (13) shown to the left of Figure 7, then bringing the edges (14) around to the position (15) and placing a few stitches at each side of the neck at A^8 as explained. The bottom 20 layer of cloth may be stitched at A^7 to the pasteboard container either before or after folding as described, and the soap face may be placed in position either before or after securing the corners of the cloth adjacent 25 the chin part of the face by a ribbon cent bow A^9 and which latter may be either pinned or stitched across the meeting corners of the cloth at this point.

In forming the open neck for the soap 30 face as described, the cloth is naturally drawn away from the upper corners thus reducing the width above the shoulders A^5 as shown in Figure 1. If desired an additional stitch or bow and stitch may be placed 35 at the edge of the face opening as shown at (16) to slightly more contract the edge of the opening.

In some cases the container (C) instead

of being an ordinary paste board box may 40 simulate a cradle bed or other appropriate device which will serve as a container, at the same time lend novel appearance to the assembly. Certain other changes and additions may also be made without departing 45 from the spirit of the invention which resides briefly in utilizing the existing materials, which are ordinarily produced for one purpose, converting them into another purpose without destroying their usefulness as originally intended and at the same time 50 enabling them to produce an unique novelty. Possibilities of the assembly are such as to create a ready sale of the device since purchasers will realize that although they are primarily purchasing a novelty doll the 55 cost price will be well within a reasonable charge for the material alone.

I claim:

1. A novelty doll made from a cloth and a loose head, the cloth being folded around the head in simulation of a body and exposing the face to view, means securing the cloth in position around the head, a box in which the doll is placed and means securing the body of the doll to the box at a point 60 adjacent the head.

2. A novelty doll made from a wash cloth and a cake of soap, the cloth being folded around the edge of the cake of soap in simulation of a hooded cape, and exposing one 70 side of the soap to view to simulate a face, means securing the cloth about the soap, a box in which the doll is placed, and means securing the cloth to the box under the cake of soap.

LULU CASE.
